COMBINATION PENDANT AND PERFUME CONTAINER

John Konjoian, Cranston, R. I., assignor to Westminster Jewelry Mfg. Co., Providence, R. I., a corporation of Rhode Island

Application October 31, 1957, Serial No. 48,289

Term of patent 3½ years

(Cl. D86—10)

FIG. 1

FIG. 2

FIG. 4

FIG. 3

Fig. 1 is a perspective view of a combination pendant and perfume container embodying my new design.

Fig. 2 is a view similar to Fig. 1 with the container in open position.

Fig. 3 is a bottom plan view of the container.

Fig. 4 is a top plan view thereof.

The broken line showing is for illustrative purposes only.

I claim:

The ornamental design for a combination pendant and perfume container, as shown and described.
